[57] **CLAIM**

The ornamental design for a dental handle, as shown and described.

DESCRIPTION

FIG. 1 is a perspective view of a dental handle showing our new design, the broken lines are for illustrative purposes only and form no part of the claimed design;

FIG. 2 is a side elevational view of FIG. 1, the other side being identical;

FIG. 3 is a top plan view thereof, the bottom being identical;

FIG. 4 is an end view thereof, the other end being identical;

FIG. 5 is a perspective view of a second embodiment of the dental handle;

FIG. 6 is a perspective view of a third embodiment of the dental handle;

FIG. 7 is a partial perspective view of a fourth embodiment of the dental handle showing a different style of knurling;

FIG. 8 is a partial perspective view of a fifth embodiment of the dental handle showing a different style of knurling; and,

FIG. 9 is a partial perspective view of a sixth embodiment of the dental handle.
